JOHN T. SCHAAFF, OF WASHINGTON, DISTRICT OF COLUMBIA, ASSIGNOR TO UNION TYPEWRITER COMPANY, OF ILION, NEW YORK, A CORPORATION OF NEW YORK.

TYPE-WRITING MACHINE.

992,263

Specification of Letters Patent. Patented May 16, 1911.

Application filed February 3, 1910. Serial No. 541,943.

To all whom it may concern:

Be it known that I, JOHN T. SCHAAFF, citizen of the United States, and resident of Washington, in the District of Columbia, have invented certain new and useful Improvements in Type-Writing Machines, of which the following is a specification.

My invention relates especially to tabulating mechanism for typewriting machines and the main object of said invention is to provide an improved and simple column selecting mechanism which enables the traveling element or carriage to be released and moved to a predetermined one of a plurality of columnar positions, any intervening columnar positions being skipped or passed.

To the above and other ends my invention consists in the features of construction, combinations of devices and arrangements of parts hereinafter described and particularly pointed out in the claims.

One form of my invention is shown in the accompanying drawings wherein—

Figure 1 is a front-to-rear vertical sectional view of a Yost visible typewriting machine embodying my invention, only so much of said machine being shown as is necessary to a clear understanding of said invention. Fig. 2 is an enlarged sectional view taken on a plane represented by the broken dotted line $x-x$ in Fig. 1 and looking in the direction of the arrows at said line. Fig. 3 is a vertical sectional view taken on a plane represented by the dotted line $y-y$ of Fig. 1 and looking in the direction of the arrows at said line. Fig. 4 is an operating view of the column selecting mechanism. Figs. 5 to 8 inclusive are fragmentary views showing the normal relation between the various column selecting levers and the part moved by said levers and controlling the variably movable frame stop. Fig. 9 is a perspective view of the column stop bar and column stops thereon.

In the various views parts are omitted and parts broken away.

While my invention is shown adapted to a front-strike typewriting machine of the Yost visible style, it is to be understood that said invention is applicable in whole or in part to other styles of writing machines.

In the present instance the main frame of the machine comprises side plates 1, a back

plate 2, a fore top plate 3 and a rear top plate 4, the top plate parts or sections being spaced apart to provide room for a carriage comprising a truck 5 and a shiftable platen frame 6, which frame is connected with said truck by links 7 and carries a platen 8. The truck 5 is provided with grooved rails 9 which coöperate through anti-friction balls 10 with fixed grooved track-ways 11. The carriage is connected by a band 12 with a spring drum 13 pivoted on brackets 14 depending from a stationary frame bar 15. Said spring drum constantly urges the carriage leftward, leftward motion being controlled by devices including a horizontal feed rack 16 supported by arms 17 pivoted to the carriage at 18 and depending from the underside thereof so that the rack bar may be swung fore and aft of the carriage. The front edge of the rack bar is toothed and said rack bar is normally held in the Fig. 1 position by a spring-pressed plunger 19 on the truck 5, said plunger pressing down on a branch 20 of an arm 17, the normal position being determined by a stop pin 21 which coöperates with another branch 22 of said arm 17. The feed rack normally meshes with a pinion 23 on the upper end of a vertical shaft 24 journaled on an arm 25 fixed to the frame bar 15, the lower end of said shaft being journaled on an adjustable stud 26 threaded through an ear on a stationary frame bar 27 supported on the frame plates 1. The escapement wheel 28 is operatively connected with the shaft and is adapted to coöperate with the usual or suitable feed dogs (not shown) which are controlled by printing and spacing keys. The shaft 24 carries a cylindrical housing 29 which contains or may contain pawl and ratchet mechanism, which, while connecting the escapement wheel with the shaft during the advance of the carriage leftward, permits rotation of the shaft independently of the escapement wheel during return movements of the carriage. The latter, of course, is normally under the control of the feeding or escapement devices whereof the escapement wheel is an element.

The mechanism for releasing the carriage comprises a shoe 30 formed on the upper end of a lever arm 31 secured to a rock shaft 33 journaled on a bracket 34 depending from

the frame bar 15, said shoe standing in front of the feed rack 16. The rock shaft 33 has fixed to it a forwardly projecting arm 35 which is connected by a link 36 with the universal bar of the column selecting mechanism, as presently to be described. By raising the link 36 the shoe 30 is swung rearward, thereby disconnecting the feed rack from the pinion.

10 The tabulating mechanism comprises a toothed stop bar 37 supported on two brackets 38 and 39 which are secured to the carriage truck 5 by screws 40. The stop bar 37 is rectangular in cross section and is slidably mounted so that it may move to a limited extent lengthwise of and relatively to the carriage for the purpose of diminishing the shock due to the impact against a frame stop of one of the column stops carried by said 15 bar. The slidable mounting comprises a piston head 41 fixed to the right-hand end of the stop bar 37 and co-operating with a fixed cylinder 42, a coiled spring 43 being interposed between the piston head and the head 20 of the cylinder. The construction thus briefly described is in the nature of a dash pot and is more fully set forth and is claimed in my co-pending application Serial No. 525,698, filed November 1, 1909. The stop 25 bar 37 is notched or toothed at its forward and rear faces, the interdental spaces being a letter space distance apart as is common and adapted to receive adjustable column stops of which four are shown in the present 30 instance and numbered from left to right 44, 45, 46 and 47. Each of these column stops comprises a notched or bifurcated sheet metal strip or plate having an angular stiffening flange and which may be arranged to 35 straddle the stop bar 37 between the teeth thereof at any desired point, said column stops being slipped on said stop bar from above. Each column stop has an edge portion bent off at right angles to form a stiffening flange 48 and is provided with a depending portion or lug which constitutes the 40 stop portion proper of the stop. These lugs are separately numbered for convenience of description as 44^a, 45^a, 46^a and 47^a. As will 45 be apparent from Figs. 1, 4 and 9, they all terminate in a single horizontal plane but are out of line with one another, each moving in a different path, all the paths being parallel. In the present instance the lugs 50 or stops proper are so disposed that they leave an open space "s" directly beneath the stop bar, the stop lugs 44^a and 46^a being forward of said open space while stop lugs 45^a and 47^a are back of the same.

55 Adapted to co-operate with the column stops is a frame stop or column selecting stop in the form of a flat plate-like arm 49 which extends upward through a hole in the top plate 4 through a notch 50 in a guide plate 51 secured to the upper face of said top plate by screws 52. The stop arm 49 is arranged edgewise in the direction of carriage travel and normally its upper end or stopping portion lies in the open space or pathway *s* as best shown in Fig. 1 and so that a forward or rearward movement will bring it into the path of one or another of the column stop lugs. The stop arm 49 extends downward, it being slightly curved or off-set rearward and is detachably secured at its 70 lower end by screws 53 to a seat formed at the upper end of a lever frame 54, said frame inclining downward and forward and being pivoted on pivot screws 55 which are supported on the arms of a bracket 56 fixed to and depending from the frame bar 15. As best appears in Fig. 3 the lever frame is arranged between the arms of the bracket 56 and below the pivot screws 55 is bifurcated to provide two branches or arms 57, said 75 arms terminating at their lower ends in hubs which support a cross rod 58, said cross rod connecting the arms 57 of the lever frame.

80 The lever frame 54 and stop arm 49 are adapted to be variably controlled through the cross rod 58 by column selecting levers of which four are shown in the present instance and numbered respectively 59, 60, 61 and 62. These column selecting levers are of the first order and are arranged side by side and extend fore and aft of the machine, being seated in vertical notches or kerfs 63 formed in a lug or downward extension 64 from the underside of the frame bar 27. Ears 65 projecting forward from the frame bar 27 are spaced apart as shown in Fig. 2 and support pivot pins 66 which are secured in place by screws 67 and provide bearings for a rod or shaft 68, said shaft being the pivot or fulcrum of the column selecting levers. Forward of the fulcrum 68 the column selecting levers are fanned or spread apart somewhat, the forward end of each lever engaging in a slot in a vertical key stem 69, which is guided by 100 fixed guide plates 70 and 71, each key stem terminating at the top in a finger key or button 72. The keys 72 are arranged in a row above and behind the last row of the regular set of keys and the top of each key 72 may be suitably marked. As shown in Fig. 2 the top of the key associated with the lever 59 is marked with the numeral "1," while the keys associated with the levers 60, 61 and 62 are marked respectively with the numerals 115 "2," "3" and "4." The rear end portion of each of the column selecting levers where it underlies the cross rod 58 is widened somewhat as indicated at 73 and back of the widened portion 73 each lever is provided with an upward extension or finger 74 which is bent rearwardly at its top and has secured to it the upper end of a coiled restoring 120 125

spring 75, the lower end of said spring being hooked in a bracket 75^a fixed to the back plate 2. It will be understood that when any of the finger keys 72 is depressed the corresponding column selecting lever will be rocked on its fulcrum, the rear arm of said lever being raised so that it stretches the spring 75 and lifts the upper edge of the thickened portion 73 of said lever toward the cross rod 58. Said upper edge of each lever is formed with a cam slot, these cam slots varying in direction and inclination, as will be clear from Figs. 5 to 8 inclusive; but the mouths of the cam slots being in line and normally underlying the cross rod 58 so that when raised separately they may engage therewith. The cam slot 76 in the lever 59 inclines downward and rearward at such an inclination that when the lever 59 is operated and the cam slot engages with the rod 58, it will cam said rod rearward to the extent shown by the dotted line position of said rod in Fig. 5. The cam slot 77 in the lever 60 inclines oppositely to the slot 76 so that said slot 77 is adapted to swing the cross rod 58 forward to the dotted line position in Fig. 6. The cam slot 78 in the lever 61 is directed rearward like the cam slot 76 but at a lesser inclination, while the cam slot 79 in the lever 62 inclines forward but at a lesser inclination than the other forwardly inclined cam slot 77 so that it will swing the cross rod 58 forward to a lesser degree. The construction is such that the cam slot 76 will coöperate with the rod 58 to swing the lever frame 54 on its fulcrum and throw the stop arm 48 forward into the path of the column stop lug 44^a. The cam slot 78 will operate to throw the stop arm 49 forward to a lesser extent and into the path of the stop lug 46^a; while the two cam slots 77 and 79 will operate to swing the stop arm 49 rearward different extents and so that it will coöperate respectively with the column stop lugs 45^a and 47^a.

The actuation of the column selecting levers not only variably actuates the stop arm 49 so as to move it different extents in the arcuate path to which it is confined, but also lifts the link 36 to effect the release of the carriage through devices comprising a bail-like universal bar member 80 which overlies the column selecting levers forward of the cam slots therein, said universal bar member having forwardly projecting portions which are turned oppositely inward to engage with bearing openings or depressions in the ends of the lug 64. The lower end of the link 36 is pivotally connected to this universal bar member at the right-hand side thereof so that an actuation of any column selecting lever will swing the universal bar member upward on its pivots and lift the link 36 to release the carriage. A

rearwardly extending angular arm 80^a is fixed centrally to the universal bar frame 80 and is connected to a restoring spring 81 anchored to the bracket 75^a.

After the detailed description of my improvements heretofore given it is not deemed necessary to enter into a further extended explanation of the mode of operation. In Fig. 4 the parts are shown in operative or abnormal positions resulting from the actuation of the fourth column selecting key 75 which operates through the cam slot 79 to swing the stop arm 49 rearward into the path of the column stop lug 47^a and also to release the carriage so that the same may run freely leftward until arrested by the co-action of the stop 49 with the stop lug 47^a, the stop 49 being held locked in co-acting position by the engagement of the bottom of the slot 79 with the cross-rod 58 as long as the column key is held depressed. During this leftward run the intervening column stop lugs whose paths are not obstructed by the frame stop 49 will be skipped or passed. It will be understood that a similar actuation of any of the other column keys will move the frame stop to a different extent and cause its co-action with that one of the column stops which corresponds with the actuated column key. The arm 80^a has a cam notch which acts on the rod 58 to return the frame stop always to normal position and hold it therein.

It will be seen that my invention provides a simple and effective column selecting mechanism which is rapid and certain in operation and which is adapted to various styles of work, such for example, as writing in the date, name and address and the salutation, etc., in letters, or the name and address on envelopes as well as for form or tabular work of various kinds.

Certain features of construction herein shown are not broadly claimed as they form in part the subject-matter of my aforesaid co-pending application Serial No. 525,698.

What I claim as new and desire to secure by Letters Patent, is:—

1. In a typewriting machine and in tabulating mechanism, the combination of column stops movable in different lines of travel, and a column selecting stop confined to an arcuate path and movable from a middle position transversely of said lines of travel in opposite directions and into the paths of selected column stops.

2. In a typewriting machine and in tabulating mechanism, the combination of column stops, the stopping portions whereof have different lines of travel and are arranged to leave an open space intermediate certain of said lines of travel, and a co-active stop arranged normally in said open space, and means for moving said co-active stop

variably to co-act with predetermined column stops.

3. In a typewriting machine and in tabulating mechanism, the combination of a stop bar toothed at opposite sides, a plate-like column stop notched and bifurcated to straddle said stop bar and fit between the teeth thereof, said plate-like stop being provided with a stiffening flange bent off at 10 right angles from the stopping portion of said column stop, said flange being separated from said stop bar, and a stop co-active with said column stop.

4. In a typewriting machine and in tabulating mechanism, the combination of column stops terminating in a single plane and movable in separate lines of travel, and a pivoted column selecting stop movable on its pivot transversely of said lines of travel into 20 the paths of selected column stops.

5. In a typewriting machine and in tabulating mechanism, the combination of column stops all terminating in a single plane but movable in separate lines of travel, a 25 column selecting stop having a fixed pivot, and means for swinging said column selecting stop variably on its pivot transversely of said lines of travel and into the paths of selected stops.

30 6. In a typewriting machine and in tabulating mechanism, the combination of a stop bar, column stops adjustable thereon, the stop portions of said stops being out of line and arranged at opposite sides of an open 35 space, a co-active stop normally held in said open space, and means controlled by a plurality of keys for variably moving said co-active stop in opposite directions transversely of the lines of travel of said column 40 stops and into the paths of predetermined stops.

7. In a typewriting machine and in tabulating mechanism, the combination of a plurality of column stops movable in separate 45 lines of travel, a lever frame having a fixed fulcrum and terminating at one end in a co-active stop, and key controlled means for cooperating with the opposite end of said lever to move the co-active stop oppositely 50 from a central position to bring it into the paths of any predetermined stop of the plurality of column stops.

8. In a typewriting machine and in tabulating mechanism, the combination of a plurality of column stops movable in separate 55 lines of travel, a lever frame having a fixed fulcrum and having fixed to it at one end a co-active stop, and a plurality of key controlled cams co-operative with the opposite 60 end of said lever frame to swing it variably on its pivot.

9. In a typewriting machine and in tabulating mechanism, the combination of a plurality of column stops movable in separate

lines of travel, a lever frame having a fixed 65 fulcrum and having a stop fixed at one end, and a plurality of column selecting levers each provided with a cam slot, said cam slots co-acting with said lever frame to swing it variable extents on its fulcrum. 70

10. In a typewriting machine and in tabulating mechanism, the combination of a plurality of column stops movable in separate 75 lines of travel, a lever frame having a fixed fulcrum and having fixed to it at one end a co-active stop, the opposite end of said lever frame being provided with a cross rod, and a set of column selecting levers each provided with a stop co-active with said cross rod. 80

11. In a typewriting machine and in tabulating mechanism, the combination of a traveling carriage, a stop bar thereon, a plurality of column stops adjustable thereon and having their stop faces out of line with 85 each other, a lever frame having a fixed pivot and carrying a stop co-active with said column stops and confined to an arcuate path, a cross rod on said lever frame, and a set of key controlled levers each 90 having a cam slot, the cam slots being variably arranged and operative on said cross rod to swing said lever frame variable extents. 95

12. In a typewriting machine and in tabulating mechanism, the combination of a traveling carriage, a stop bar thereon, a plurality of column stops adjustable thereon and having their stop faces out of line with each other but terminating in a single plane, 100 a lever frame having a fixed pivot and carrying a stop co-active with said column stops and confined to an arcuate path, a cross rod on said lever frame, and a set of 105 column selecting levers of the first order controlled by depressible keys and provided with cam slots, the cam slots being variably inclined and adapted to operate variably said lever frame.

13. In a typewriting machine and in tabulating mechanism, the combination of a plurality of column stops, a lever frame, a detachable co-active stop fixed thereon, said lever frame being provided with branches connected by a cross rod, and key controlled 110 slotted levers operative on said cross rod to actuate said lever frame, each slotted lever moving said lever frame a different extent from every other slotted lever. 115

14. In a typewriting machine and in tabulating mechanism, the combination of a traveling carriage, disconnectible carriage feeding devices, column stops, a lever frame carrying a co-active stop, a set of column selecting levers for actuating said 120 lever frame to co-act in predetermined column stops, said column selecting levers being of the first order and controlled by 125

depressible keys, a pivoted universal bail overlying said column selecting levers, a shoe for disconnecting said carriage feeding devices, and connections between said shoe and said universal bail comprising a link pivoted on said bail.

Signed at the borough of Manhattan, city

of New York, in the county of New York and State of New York, this 2nd day of Feb. A. D. 1910.
